(57) **CLAIM**

The ornamental design for door lever, as shown and described.

DESCRIPTION

FIG. 1 is a side perspective view of a door lever according to my new design.

FIG. 2 is a left end view of the door lever as in FIG. 1.

FIG. 3 is a right side view of the door lever as in FIGS. 1-2.

FIG. 4 is a top view of the door lever as in FIGS. 1-3.

FIG. 5 is a bottom view of the door lever as in FIGS. 1-4.

FIG. 6 is a front view of the door lever as in FIGS. 1-5; and, FIG. 7 is a rear view of the door lever as in FIGS. 1-6.

The design of the present invention and as shown in FIGS. 1-7 is an ornamental door lever.
